METAL FEEDING MECHANISM FOR TYPE-FORMING MACHINES

Henry G. Nichols, North Wilkesboro, N. C.

Application March 16, 1939, Serial No. 262,274

1 Claim. (Cl. 22—80)

My invention relates to type-forming machines and more particularly to devices for feeding a pig of metal to the melting pot of said machine.

One of the principal objects of my invention is to provide a metal feeder adapted for association with a type-forming machine and which is so constructed and arranged as to automatically feed a pig of metal to the melting pot of said machine.

10 Another object of my invention is to provide a device of the above described character equipped with means for automatically controlling the feed of the metal to the melting pot in a manner whereby the molten metal in the melting pot may 15 be maintained at a desired level.

A further object of my invention is to provide a device of the character described equipped with signalling means whereby the operator of the machine is warned when the supply of pig metal 20 becomes exhausted.

An important object of my invention is to provide a device of the character described which is simple in construction, durable in operation, efficient in use, and economical in manufacture.

25 Another important object of my invention is to provide a device of the character described which is readily attachable to type-forming machines already in use without modifying the latter.

30 Other objects and advantages will be apparent from the following description, appended claim and annexed drawings.

Referring to the drawings wherein like reference characters designate like parts throughout 35 the several views:

Figure 1 is a side elevation of my invention illustrating the latter attached to a portion of a type-forming machine.

Figure 2 is an end elevation of my invention.

40 Figure 3 is an enlarged longitudinal sectional view of my invention illustrating the parts in non-feeding position.

Figure 4 is a detail sectional view taken on the line 4—4 of Figure 3.

45 Figure 5 is a detail sectional view of the adjustable sleeve for effecting connection between the pump operating arm and the arm for operating the feeding machine.

Figure 6 is a detail sectional view taken on the line 6—6 of Figure 2.

In teaching my invention, as illustrated in Figure 1 of the drawings, I provide a portion of a type-forming machine of ordinary construction and which is equipped with the usual melting pot 6 having contained therein a pump 7 pro-

vided with the usual piston rod 8, the latter being connected to a pump actuating rocker arm 9 mounted on a shaft 10, it being understood that said shaft is operated by the type-forming machine to effect reciprocation of the piston rod 8 and subsequent actuation of the pump 7 in the usual manner for discharging molten metal from the pot 6 for forming types or slugs.

The portion of the machine illustrated is provided with a top having an offset section and 10 which forms a base 11 for the support of my device which comprises a frame having upwardly and inwardly extending legs 12, the latter being connected at their upper ends to a deck 13 formed with vertical and horizontal sections 14 and 15 respectively. The upper end of one of said legs is fashioned with a rib terminating in a bearing 16 through which extends a shaft 17, the latter being fixed to said bearing 16 against rotation by means of a nut 18 threaded on the end of 20 said shaft adjacent said bearing.

Rotatably mounted on the shaft 17 is a cat-head 19, the latter being formed with a ratchet wheel 20 and with spaced chain receiving channels 21 and 22 in which are carried chains 23 25 and 24 respectively having upper ends connected to said cat-head for a purpose hereinafter set forth. Interposed between the cat-head and section 14 is a brake drum 25, the latter being fashioned on the periphery thereof, adjacent said section 14, with a ratchet gear 26 and the face of said drum adjacent said cat-head 19 has pivotally mounted thereon a pawl 27 for engagement with the teeth of the ratchet wheel 20 as clearly illustrated in Figures 1, 2 and 3 of the 35 drawings. A spring 28 carried by the drum connects the latter to said pawl and serves to maintain the pawl in engagement with the wheel 20.

Pivotally mounted on the section 15, of the deck 13, is a bell crank 29, one end of which has 40 pivoted thereto a brake shoe 30 for engagement with the brake drum 25 whereby to normally maintain the latter against rotation. The opposite end of the crank 29 has pivoted thereto the upper end of a bolt 31 which slidably extends 45 vertically through the section 15 and has secured on the lower end thereof a wing nut 32. Mounted on the bolt between the nut 32 and section 15 is a coil spring 33 serving to tension the shoe 30 against the drum 25. Obviously, by adjusting the 50 nut 32 the tension of the spring is varied together with the tension of the shoe relative to the drum.

The chains 23 and 24 extend downwardly through openings 34 and 35 respectively in the section 15 and the lower end of the chain 24 is 55

provided with a finger ring 36 of a diameter to preclude said ring passing through the opening 35 when the chain 24 is actuated upwardly as hereinafter more fully described. The lower end 5 of the chain 23 is provided with a hook 37 which is attached through the eyed upper end of a pig of metal 38 adapted to be fed into the melting pot 6 and said pig of metal serves as a weight for effecting rotation of the cat-head upon rotation 10 of said drum as hereinafter set forth.

Adjustably mounted on the rocker arm 9 is a sleeve 39, the latter being pivoted to the lower end of a lower feed arm 40, the upper end of which is adjustably and pivotally connected to 15 a link 41 pivoted to one of the legs 12 as clearly illustrated in Figures 1 and 3. A screw 42 is provided in the sleeve 39 whereby to maintain said sleeve in adjusted position on the arm 9. Also adjustably and pivotally connected to the link 20 41 is the lower end of an upper feed arm 43, the upper end of which is formed with a pawled section 44 for engagement with the teeth of the ratchet gear 26. Obviously, actuation of the 25 rocker arm 9 to effect discharge of the molten metal from the melting pot 6 causes reciprocation of the feed arms 40 and 43 which in turn, through the medium of the pawled section 44, serves to effect rotation of the drum 25 against the tension of the shoe 30. Rotation of the drum 30 25 permits rotation of the cat-head 19 for the reason that the ratchet wheel 20 follows the pawl 27 due to the weight of the pig of metal 38. Rotation of the cat-head 19 serves to effect lowering of the pig of metal into the melting pot for 35 melting therein, it being understood that substantially the same amount of metal is discharged from said melting pot by the pump as is introduced therein through the lowering of the pig of metal therewithin.

40 By adjusting the arms 40 and 43 relative to the link 41 and the sleeve 39 relative to the arm 9 the operator can insure a like amount of metal being introduced into the melting pot as is discharged therefrom. However, to preclude accidental overflowing of the melting pot, I provide 45 therein a float 45, the latter having secured thereto the lower end of a rod 46. The upper section of the rod 46 extends through the lower end of a bracket 47 mounted on the leg 12 above the link 41. Said upper section of the rod 50 46 is provided at the upper end with a hook 48 connected to the lower end of a chain 49 trained over a pulley rotatably mounted on the upper end of the bracket 47.

55 The opposite end of the chain 49 is detachably connected to the hook-end of a bolt 50, the opposite end of which extends through the arm 43 and is provided thereon with an adjusting nut 51. A spring 52 is mounted on the bolt 50 between said hook-end and the arm 43 and serves to maintain the nut 51 in engagement with the arm. By adjusting the nut 51, the hook-end of the bolt may be actuated in a direction away from or towards said arm as desired. Should 60 the molten metal in the melting pot rise above a predetermined level by an accelerated lowering of the pig of metal therein, the float will likewise rise and cause a similar movement of the rod 46 thereby permitting slack in the chain 70 49.

As illustrated, the arm 43 extends upwardly and outwardly relative to the deck 13, thus, when slack occurs in the chain 49, the arm 44 will, by gravity, be moved outwardly and out of engagement with the ratchet gear 26 thereby precluding

further rotation of the drum 25 until the float 5 lowers sufficiently to take up the slack in the chain 49 and actuate the arm 43 into engagement with the ratchet gear 26.

When the pig of metal has been completely 5 lowered into the pot 6, the finger ring 36 engages the deck 13 and prevents further rotation of the cat-head through the medium of the chain 24 and thereby effects ratcheting of the pawl 27 over the teeth of the wheel 20 upon rotation of 10 the drum 25.

Therefore, in order to warn the operator of the machine that the pig of metal is exhausted, I provide a signal device which comprises a gong 53 mounted interiorly of the drum 25 and which 15 has associated therewith a clapper 54 provided with an arm extending through a slot 55 in the side wall of the drum and fixed to the pawl. Ratcheting of the pawl over the teeth of the wheel 20 serves to actuate the clapper and ring 20 the gong, thus signalling the operator of the exhaustion of the pig of metal.

When the pig of metal has become exhausted, the operator by actuating the chain 24 downwardly through the medium of the finger ring 25 36 effects rotation of the cat-head in a clockwise direction relative to the drum 25 and disposes the hook 37 of the chain 23 in raised position for having attached thereto another pig of metal. A finger ring 56 is secured within the length of 30 the chain 23 and serves as a stop member to limit the upward movement of the chain and also to permit ready adjustment of the chain when it is desired to manually lower the pig of metal.

The float also serves to effect engagement of 35 the pawled section 44 of the rod 43 with the gear 26 at a point thereon sufficient to cause lowering of the chain so that the same quantity of metal is introduced into the pot as is discharged therefrom even though the arm 43 makes a complete 40 stroke.

The lower end of the leg on which the bracket 47 is secured is fashioned with a slot for accommodating therethrough a set screw 57 carried by a projection on the base 11 whereby the frame 45 may be securely attached and adjusted thereon. The opposite leg is formed with a plurality of openings and through one of which the arm 43 extends and the wall of said opening serves to limit the outward movement of said arm when 50 the latter is disengaged from the ratchet gear 26 upon actuation of the float 45.

From the foregoing it will be apparent that I have provided a simple and efficient device for automatically lowering pigs of metal within a 55 melting pot and which may be readily attached to type-forming machines of various standard types without modifying the latter.

It is to be distinctly understood that various 60 changes and modifications may be resorted to in the construction of my invention without departing from the spirit of the latter or the scope of the appended claim.

What I claim is:

In combination with a type-forming machine 65 equipped with a melting pot and a rocker arm, means for continuously rocking said arm; a device for automatically feeding a pig of metal into said pot and comprising a frame supported above said pot, a drum rotatably mounted on said frame, a brake for said drum for normally maintaining said drum against rotation, a cat-head rotatably mounted on said frame adjacent said drum, a flexible element carried by said cat-head and adapted to suspend a pig of metal over said 70 75

pot in a manner whereby said pig of metal normally urges rotation of said cat-head, a pawl carried by said drum and effecting tooth connection with said cat-head for maintaining the latter against rotation by said pig of metal relative to said drum, a member connected to said rocker arm and engaging said drum for actuating the latter upon operation of said arm to permit rotation of said cat-head in urged direction by 5
10 said pig of metal whereby the latter is lowered

into said pot a float in said pot and connected to said member for moving the latter into inoperative position with respect to said drum upon raising of said float beyond a predetermined position to said pot to preclude lowering of said pig 5 of metal into said pot, and a signal device connected to said pawl and operable by the latter upon rotation of said drum relative to said cat-head.

HENRY G. NICHOLS. 10
